DESIGN FOR A DISPLAY BOX

Irving H. Fowle, Dorchester, Mass.

Application June 29, 1934, Serial No. 52,400

Term of patent 7 years

To all whom it may concern:

Be it known that I, IRVING H. FOWLE, a citizen of the United States, residing at Dorchester, in the county of Suffolk, and State of Massachusetts, have invented a new, original, and ornamental Design for a Display Box, of which the following is a specification, reference being had to the accompanying drawing, forming part thereof.

The drawing is a perspective showing the form and shape of the display box of my new design.

I claim:

The ornamental design for a display box, substantially as shown.

Signed at Lowell, in the county of Middlesex and State of Massachusetts, this 27th day of June, 1934.

IRVING H. FOWLE.
